US0D1076102S

(12) **United States Design Patent** (10) Patent No.: **US D1,076,102 S**
Shi et al. (45) Date of Patent: ** May 20, 2025

(54) **AUDIPHONE**

(71) Applicant: **Xiamen Retone Hearing Technology Co., Ltd.**, Xiamen (CN)

(72) Inventors: **Yiquan Shi**, Xiamen (CN); **Chengxiang Zhang**, Xiamen (CN)

(73) Assignee: **Xiamen Retone Hearing Technology Co., Ltd.**, Xiamen (CN)

(**) Term: **15 Years**

(21) Appl. No.: **29/882,795**

(22) Filed: **Jan. 19, 2023**

(30) **Foreign Application Priority Data**

Sep. 29, 2022 (CN) 202230650441.1

(51) **LOC (15) Cl.** **24-99**

(52) **U.S. Cl.**

USPC **D24/174**

(58) **Field of Classification Search**

USPC D24/173-175, 106, 133, 141; D14/205, D14/223, 230

(57) **CLAIM**

The ornamental design for an audiphone, as shown and described.

DESCRIPTION

FIG. 1 is a perspective view of an audiphone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom side view thereof; and,

FIG. 8 is a perspective view thereof when used.

The broken lines depict portions of the audiphone that form no part of the claimed design.

1 Claim, 8 Drawing Sheets
